UNITED STATES PATENT OFFICE.

LOYD R. STOWE, OF ST. LOUIS, MISSOURI.

WATER TUBE BOILER.

Application filed August 30, 1920. Serial No. 407,046.

This invention relates to water tube boilers, wherein banks of water circulating tubes are exposed to the products of combustion and communicate with drums or headers at their opposite ends; and it relates more particularly to the bank of tubes for the last or back pass of the boiler.

One of the principal objects of the present invention is to increase the number of tubes in a bank and obtain a close spacing thereof, so as to obtain a greater heating surface and a more efficient utilization of the products of combustion. Another object is to increase the number of tubes in a bank without weakening the shells, manifolds or headers in which the tubes terminate. Another object is to increase the rate of transfer of heat from the products of combustion to the water tubes. Another object of the close spacing of the tubes is to divide the gases of combustion in small currents, thereby decreasing the distance between the center of the currents and the surfaces of the tubes and thus enabling a greater amount of heat to be extracted from the narrow currents of gas. Another object of the close spacing of the water tubes is to increase the velocity of the products of combustion over the tubes, which increases the rate of heat transfer and also tends to prevent accumulation of soot and ashes on the surfaces of the water tubes, which accumulation retards the flow of gases and acts as a heat insulator.

The invention consists principally in the arrangement of the water tubes which will permit of a close spacing of the tubes, thereby obtaining a greater efficiency in the transfer of the heat from the products of combustion to the water without weakening the drums into which the tubes are expanded and enabling the drums to withstand higher pressures. The invention also consists in the combinations and arrangements of parts hereinafter described and claimed.

In the drawings, wherein like reference numerals refer to like parts wherever they occur,

Fig. 1 is a central vertical section of a water tube boiler having a bank of water tubes in the last pass thereof constructed in

accordance with the invention and forming an economizer pass for the boiler;

Fig. 2 is a horizontal section through the last bank of tubes on the line 2-2 in Fig. 1, showing the arrangement of tube spacing; 55

Fig. 3 is a detail view showing the tube arrangement in connection with an economizer;

Fig. 4 is a horizontal section on the line 4-4 in Fig. 3; 60

Fig. 5 is a diagrammatic view showing the opposite ends of the two sets of tubes bent in opposite directions and expanded into headers; and

Fig. 6 is a view similar to Fig. 5 showing the upper and lower ends of alternate tubes bent in opposite directions and expanded into spaced upper and lower drums. 65

The water tube boiler shown in the accompanying drawings comprises a boiler setting 10, a furnace 11 having an automatic stoker 12 of the kind shown in my application Serial No. 160912 filed April 1917, patented Jan. 31, 1922, Patent No. 1,405,072, arranged therein, an ignition arch 13 and a bridge wall 14 overhanging the rear end of the stoker. Banks of generating tubes 15 and 16 have their lower ends expanded into a mud drum 17 and have their upper ends expanded into a steam and water drum 18. 70

The upper and lower ends of the banks 15 and 16 being bent so as preferably to enter the drums 17 and 18 radially. The products of combustion from the furnace 11 are directed upwardly along the tubes of the front bank 15 by means of a baffle 19, which extends upwardly back of said tubes from the mud drum 17 and terminates below the steam and water drum 18, leaving a passage between the upper edge of the baffle and the drum 18. The baffle 20 is located back of the second bank of tubes 16 and extends downwardly from the underside of the drum 18 to a point above the mud drum 17, thus leaving a passage between its lower end and the top of the mud drum. Thus, the products of combustion are directed upwardly from the furnace 12, across the top of the baffle 19, thence downwardly along the second bank of tubes 16, and thence beneath 80

the baffle 20 into the last or back pass 21 of the flue, which last pass communicates at its upper end with a smoke stack 22.

A third or rear bank of tubes, comprising two sets of tubes 23 and 24, is arranged in the back pass 21. Both sets of tubes are disposed vertically in the last pass, the sets alternating and being arranged in parallel alignment for the greater portion of their length. The upper ends of the tubes of the set 23 are expanded into the steam and water drum 18, the tubes being bent forwardly so as to enter radially into said drum. The lower ends of the set of tubes 23 are expanded into the mud drum 17 and are also bent forwardly so as to enter radially into said drum. The other set of tubes 24 have their upper ends bent rearwardly and expanded into headers 25 located near the outlet passage of the last pass. These headers are connected to the steam and water drum 18 by means of water pipes 26. The lower ends of the set of tubes 24 are extended downwardly below the mud drum 17 and are curved forwardly so as to enter radially into a second and smaller mud drum 27, which is connected to the mud drum 17 by means of a blow-off pipe 28. A series of baffles 29, which project toward each other from the rear wall of the furnace and from the rear of the baffle 20 are arranged on opposite sides of the last bank to cause the products of combustion in the last pass to travel along the bank parallel with the tubes thereof. This arrangement of expanding the lower ends of the alternate tubes of the rows or sets of the rear bank into the two mud drums 17 and 27 in the lower portion of the boiler and expanding the upper ends of the last bank alternately into the steam and water drum 18 and the headers 25, results in a very close nesting of the straight parallel portions of the tubes and a wide spacing of the bent portions thereof. The wide spacing of the bent ends of the tubes thus secured permits the distance between the tube holes in the drums to be increased; and as this distance limits the pressure that the drums are able to withstand, the increasing of this distance increases the strength of the drums. The close spacing of the tubes is not important in the front banks, as the first heat from the flame is absorbed largely by radiation and, therefore, the tubes of the front banks may be spaced farther apart to enable the tubes to be replaced when burnt out, due to the extreme heat to which they are subjected and to avoid obstructing the draft. As the products of combustion in the last pass move substantially parallel with the tubes, and as they have to pass in small currents through the narrow spaces between the tubes, the velocity is increased and the amount of heat transferred from the products of combustion to the tubes is increased thereby increasing the

amount of steam generated for a given amount of fuel consumed. This close nesting of the tubes and the baffles 29, which cause the products of combustion to flow along the nested tubes, increases the velocity of the products of combustion over the surfaces of the tubes and tends to prevent the accumulation of soot and ashes thereon.

Figs. 3 and 4 show the tube arrangement in connection with an economizer. In these figures, the upper and lower ends of alternate tubes 30 and 31 are bent in opposite directions and are expanded into spaced headers 32 which may be separate from each set of tubes or may be continuous. As shown in Fig. 4, the tubes of one set are disposed with their longitudinal centers opposite the spaces between the tubes on opposite sides thereof.

In Fig. 5, the opposite ends of the tubes of one set 33 are shown bent in the same direction and expanded in the headers 34 and the opposite ends of the tubes 35 of the other set are bent in the same direction, but opposite to the bends of the first mentioned set, and are expanded into headers 36 arranged opposite to the headers 34 of the first mentioned set.

In Fig. 6, the tubes of both sets 37 and 38 have their lower ends bent in opposite directions and expanded into drums 39 and have their upper ends bent across each other and expanded into drums 40 disposed on the side opposite from the headers into which the lower ends of the tubes are expanded.

The foregoing described arrangements permit a close nesting of the tubes for a greater portion of their length, thus obtaining a greater area of heating surfaces in a given space and also increasing the velocity of the products of combustion. The wide spacing of the ends of the nested tubes permits the tube holes in the drums to be placed farther apart and enables the drums to withstand greater pressures.

The invention is not limited to boilers, but is equally adapted for use in connection with economizers, containers, superheaters, stills and similar apparatus.

What I claim is:

1. The combination with a furnace and a tortuous flue, therefor of a water tube boiler comprising upper and lower chambers and two banks of generating tubes located in the first and second passes of said flue and connecting said chambers, additional upper and lower chambers and a third bank of tubes disposed substantially vertically in the last pass, alternate tubes in said last pass being connected to said first mentioned chambers and the intermediate tubes being connected to said second mentioned chambers, said flue having baffles in its last pass arranged to reduce the sectional area substantially below the sectional area of the ini-

tial pass whereby a relatively greater proportion of the products of combustion are brought into contact with the tubes of the last pass, said upper chambers communicating with each other and said lower chambers communicating with each other.

2. A water tube boiler comprising pairs of upper and lower chambers, said upper chambers communicating with each other and said lower chambers communicating with each other, front, intermediate and rear banks of tubes connecting said chambers, and flue-forming walls separating said banks, the upper and lower ends of alternate tubes of the rear bank communicating with one chamber each of the upper and lower pairs and the upper and lower ends of the remaining tubes of said rear bank communicating with the other chambers of said upper and lower pairs, the body portions of the tubes of said rear bank being closely nested and their end portions being widely spaced at their points of communication with said chambers, and baffles arranged on opposite sides of said rear bank of tubes and stopping short thereof to cause the products of combustion to travel next to and substantially parallel to the body portion of said tubes.
3. A water tube boiler comprising a pair of steam and water chambers communicating with each other and a pair of mud chambers communicating with each other, front, intermediate and rear banks of tubes connecting the steam and water chambers with the mud chambers, the ends of alternate tubes of the rear bank communicating with one steam and water chamber of a pair and with one mud chamber of a pair and the intervening tubes communicating with the other steam and water chamber of said pair and with the other mud chamber of said pair, whereby a close nesting of the body portions of the tubes is obtained and a wide spacing is obtained at their points of communication with said steam and water chambers and with said mud chambers.
4. The combination with a furnace and a tortuous flue therefor of a water tube boiler comprising upper and lower chambers connected by banks of generating tubes, a bank of vertically disposed parallel tubes located in the last pass of said boiler and leaving unoccupied a cross-sectional area substantially smaller than the unoccupied area of the preceding passes and communicating at their opposite ends with chambers, the upper ends of alternate tubes communicating with one upper chamber and the lower ends of alternate tubes communicating with one lower chamber and the corresponding ends of the intervening tubes communicating with a different upper chamber and a different lower chamber, whereby a close nesting of the tubes is obtained along their middle portions and a wide spacing is obtained at their points of communication with said chambers, said upper chambers communicating with each other and said lower chambers communicating with each other.
5. The combination with a furnace and a tortuous flue therefor of a water tube boiler comprising two upper chambers communicating with each other and two lower chambers communicating with each other, banks of generating tubes in the first and second passes of said flue connecting one upper chamber and one lower chamber, a bank of vertically disposed parallel tubes located in the last pass of said flue and communicating at their opposite ends with upper and lower chambers, the upper ends of alternate tubes of the last pass communicating with one upper chamber and the upper ends of the intervening tubes communicating with the other upper chamber, and the lower ends of some of said tubes being connected to one of the lower chambers and the lower ends of the other tubes of said last pass being connected to the other of said lower chambers, said tubes being closely nested along their middle portions and being widely spaced at their points of communication with said chambers.
6. The combination with a furnace and a tortuous flue therefor of a water tube boiler comprising pairs of communicating upper and lower chambers connected by banks of generating tubes, a bank of vertically disposed parallel tubes located in the last pass of said boiler and communicating at their opposite ends with chambers, the ends of alternate tubes of said bank communicating with one chamber and the corresponding ends of the remaining tubes of said bank communicating with a different chamber, the tubes of said bank being closely nested along their middle portions and being widely spaced at their points of communication with said chambers, and baffles arranged in the last pass of said boiler close to and on opposite sides of said last mentioned bank of tubes, to cause the products of combustion to travel substantially parallel and in contact with the major portions of said tubes.
7. The combination with a furnace and a tortuous flue having a first pass, a second pass and a last pass therefor of a water tube boiler comprising upper and lower chambers connected by banks of generating tubes in the first and second passes of said flue, other upper and lower chambers and a bank of closely nested parallel tubes disposed vertically in the last pass of said flue and connected at their upper and lower ends with said last mentioned upper and lower chambers, said last mentioned chambers being in communication with said first mentioned chambers, the upper and lower ends of alternate tubes of said last mentioned bank communicating with said first mentioned upper and lower chambers.

lower chambers, and the upper and lower ends of the intermediate tubes of said last mentioned bank communicating with said last mentioned upper and lower chambers whereby a close nesting of the tubes is obtained between their end portions and a wide spacing is obtained at their points of communication with said chambers, and the sectional area of said last pass not occupied by the tubes being less than the unoccupied sectional area of the earlier passes. 10
